United States Patent Office

Des. 194,944
Patented Apr. 2, 1963

194,944

CANDLEHOLDER

Preston J. Frazier, Jr., Houston, Tex., assignor to Faroy, Inc., Houston, Tex., a corporation

Filed Feb. 12, 1962, Ser. No. 68,787

Term of patent 14 years

(Cl. D48—2)

FIG. 1 is a perspective view of a candleholder showing my new design;

FIG. 2 is a partial vertical cross-sectional view; and
FIG. 3 is an enlarged fragmentary detailed view of the pattern on the outside of the inner member.

I claim:

The ornamental design for a candleholder, substantially as shown.
